UNITED STATES PATENT OFFICE.

WILBUR H. NICHOLAS, OF INDIANAPOLIS, INDIANA.

SPEED-VARYING DRIVE.

1,241,004.

Specification of Letters Patent. Patented Sept. 25, 1917.

Application filed February 17, 1917. Serial No. 149,206.

To all whom it may concern:

Be it known that I, WILBUR H. NICHOLAS, a citizen of the United States, residing at Indianapolis, in the county of Marion and 5 State of Indiana, have invented a new and useful Speed-Varying Drive, of which the following is a specification.

The object of my invention is to produce a driving mechanism for driving a rotating 10 element at variable speeds by the application of successive impulses thereto through a reciprocating element, the structure being such that the direction of rotation of the driven element may be reversed without re- 15 versal of the driving element.

The accompanying drawings illustrate my invention. Figure 1 is a side elevation of an apparatus embodying the fundamental and essential elements of my invention; and 20 Fig. 2 is a plan.

In the illustration of my invention I have not attempted to show it incorporated in any special device designed for any particular purpose, but it will be readily understood 25 that the driving mechanism may be used for the purpose of many different machines, although the driving mechanism is primarily designed for the propulsion of motor vehicles of the farm tractor type.

30 In the drawings, 10 indicates a main wheel journaled upon shaft 11 and designed to receive the successive driving impulses transmitted by my improved mechanism from the power shaft 12 or any other suitable means 35 for the reciprocation of the main lever 13.

The apparatus shown in the drawings comprises four driving elements as follows: The main lever 13 is provided with a longitudinal slot 14 which receives a bar 15 which 40 forms the fulcrum of the lever and is mounted in suitable ways on the supporting frame 16 and adjustable by means of the adjusting screw 17 and nut 18. Pivoted at 20 to each lever 13 is a lever 21 which is fulcrumed 45 upon shaft 11. In the form shown in the drawings, two of the levers 21 are projected beyond the shaft 11, while the other two levers 21 are not so projected. Pivoted at 22 upon each lever 21, at some distance from 50 the fulcrum 11 of said lever, is a link 23 which is extended to a point beyond the periphery of wheel 10 and carries a shoe 24.

The distance between pivot 22 and the working face of shoe 24 is slightly greater 55 than the shortest distance between said pivot and the circumferential face of wheel 10.

Pivoted at 25 on link 23 is an eye block 26 which is perforated at right angles to the axis of the pivot 25 and has a rod 27 passed through it, said rod carrying compression 60 springs 28, 28, which are balanced against each other upon the eye block 26. Each rod 27 is carried at the outer end of an arm 29, the several arms being carried by shaft 30 which may be rocked and held in either extreme of adjustment by means of lever 31.

Assuming the parts to be in the position shown in the drawings, it will be apparent that reciprocation of lever 13 will cause reciprocation of the associated lever 21. Referring particularly to the lever 21 which is nearest the observer in Fig. 1 of the drawings, it will be seen that an upward movement of the righthand end of this lever will first cause a swinging of link 23, and, as the 75 outer end of this link is supported between the ends of its buffer springs 28, the downward movement of the lefthand of lever 21 will first cramp shoe 24 tightly upon wheel 10 and will then cause wheel 10 to advance 80 in the direction indicated by the arrow. The opposite movement of lever 21 will first cause an outward movement of shoe 24 from the circumference of wheel 10 so as to release the grip on the wheel, and then permit a return of the shoe to its initial position by the action of the lower spring 28, which has been compressed during the forwarding action upon wheel 10. In the meantime, the associated duplicate driving elements have 90 been operating in a similar manner, so that with the four driving elements shown, a substantially uniform rotation of wheel 10 is obtained. It will, of course, be understood that, with the parts in the position shown 95 in the drawings, the two middle levers 21 will accomplish forwarding movement of the wheel 10 on their upper strokes.

In order to reverse the direction of movement of wheel 10, lever 31 will be swung so 100 as to shift arm 29 to the positions indicated in dotted lines in Fig. 1, thereby swinging all of the links 23 about their respective pivots 22 to positions on the opposite sides of the medial lines of the levers 21, whereupon reciprocation of levers 21 will have an opposite rotative effect upon wheel 10.

I claim as my invention:

1. The combination of a rotating member having a circumferential face, a lever pivoted adjacent said member, means for applying a driving force to said lever, a link piv-

oted to said lever at a point other than its fulcrum, a shoe carried by said link and adapted to engage the circumferential face of the rotative member, and means for yieldingly supporting the outer end of said link, for the purpose set forth.

2. The combination of a rotative member having a circumferential face, a lever pivoted adjacent said member, means for applying a driving force to said lever, a link pivoted to said lever at a point other than its fulcrum, a shoe carried by said link and adapted to engage the circumferential face of the rotative member, a support for the outer end of said link, said support comprising a pair of opposed springs, and means for shifting said support so as to normally hold the link angularly displaced, to one side or the other, with relation to the medial line of the first-mentioned lever.

3. The combination of a rotative member having a circumferential face, a lever pivoted adjacent said member, means for applying a driving force to said lever, a link pivoted to said lever at a point other than its fulcrum, a shoe carried by said link and adapted to engage the circumferential face of the rotative member, a support for the outer end of said link, and means for shifting said support so as to normally hold the link angularly displaced, to one side or the other, with relation to the medial line of the first-mentioned lever.

4. The combination of a rotative member having a circumferential face, a lever pivoted adjacent said member, a link pivoted to said lever at a point other than its fulcrum, a shoe carried by said link and adapted to engage the circumferential face of the rotative member, means for yieldingly supporting the outer end of said link, an operating lever connected to the first-mentioned lever,

and a shiftable fulcrum for said operating lever, whereby the throw of the first-mentioned lever may be varied.

5. The combination of a rotative member having a circumferential face, a lever pivoted adjacent said member, a link pivoted to said lever at a point other than its fulcrum, a shoe carried by said link and adapted to engage the circumferential face of the rotative member, a support for the outer end of said link, said support comprising a pair of opposed springs, means for shifting said support so as to normally hold the link angularly displaced to one side or the other, with relation to the medial line of the first-mentioned lever, an operating lever connected to the first-mentioned lever, and a shiftable fulcrum for said operating lever, whereby the throw of the first-mentioned lever may be varied.

6. The combination of a rotative member having a circumferential face, a lever pivoted adjacent said member, a link pivoted to said lever at a point other than its fulcrum, a shoe carried by said link and adapted to engage the circumferential face of the rotative member, a support for the outer end of said link, means for shifting said support so as to normally hold the link angularly displaced, to one side or the other, with relation to the medial line of the first-mentioned lever, an operating lever connected to the first-mentioned lever, and a shiftable fulcrum for said operating lever, whereby the throw of the first-mentioned lever may be varied.

In witness whereof, I have hereunto set my hand at Indianapolis, Indiana, this 14th day of February, A. D. one thousand nine hundred and seventeen.

WILBUR H. NICHOLAS.
